(57) **CLAIM**

The ornamental design for a golf cleat, as shown and described.

DESCRIPTION

FIG. 1 is a bottom view in perspective of a first embodiment of a golf cleat showing my new design

FIG. 2 is a bottom view in plan thereof;

FIG. 3 is a top view plan thereof; and,

FIG. 4 is a side view in elevation thereof.

The broken lines in the Figures are for illustrative purposes only and form no part of the claimed design.

1 Claim, 2 Drawing Sheets

FIG. I

FIG.2

FIG.3
